DESIGN FOR A COMBINATION CAN PUNCH AND SEALER

Howard Lester Atkinson, Green Bay, Wis.

Application April 3, 1945, Serial No. 118,845

Term of patent 7 years

(CL. D22—2)

To all whom it may concern:

Be it known that I, Howard Lester Atkinson, a citizen of the United States, residing at Green Bay, in the county of Brown, and State of Wisconsin, have invented a new, original, and ornamental Design for a Combination Can Punch and Sealer, of which the following is a specification, reference being had to the accompanying drawing, forming part thereof.

Figure 1 is a front elevational view of a com-

bination can punch and sealer, showing my new design,

Figure 2 is a side plan view,
Figure 3 is a bottom elevational view, and
Figure 4 is a top plan view thereof.

I claim:

The ornamental design for a combination can punch and sealer, as shown.

HOWARD LESTER ATKINSON.
